UNITED STATES PATENT OFFICE.

CHARLES ALGERNON PARSONS AND STANLEY SMITH COOK, OF WALLSEND-ON-TYNE,
ENGLAND; SAID COOK ASSIGNOR TO SAID PARSONS.

STEAM SUPERHEATER.

1,421,712.

Specification of Letters Patent Patented July 4, 1922.

Original application filed April 27, 1917, Serial No. 165,048. Divided and this application filed June 26, 1918. Serial No. 242,105.

To all whom it may concern:

Be it known that we, CHARLES ALGERNON PARSONS and STANLEY SMITH COOK, both subjects of the King of Great Britain and 5 Ireland, and both residing at Turbinia Works, Wallsend-on-Tyne, in the county of Northumberland, England, have invented certain new and useful Improvements in and Relating to Steam Superheaters, of which

10 the following is a specification.

The present invention relates to improvements in steam superheaters.

As ordinarily constructed, superheaters consist of tubes or chambers so disposed as 15 to be exposed externally to the flames or hot gases of combustion, and so connected that the steam passes through them on its passage from the boiler to the engine, whereby the steam is increased in temperature by the 20 desired amount.

Difficulty has been experienced in the operation of such plants through the superheater acquiring an excessive temperature when the demand for steam either ceases or 25 is reduced. This difficulty is particularly serious when the utilization of steam is only temporarily suspended, as under such circumstances when the regulating valves are again opened, the very high temperature 30 steam from the superheater is liable to cause considerable damage to the engine parts.

These dangers are not in any way overcome by the fact that the boiler is provided with safety valves, because, although surplus 35 steam generated in the boiler by excessive heat in the furnaces will blow off through the relief valves as the pressure increases, no passage of fresh steam takes place through the superheater, which therefore continues to 40 rise in temperature.

The object of the present invention is to provide automatic means for preventing excessive heating of the superheater tubes, when the ordinary consumption of steam is 45 reduced or ceases by regulating or closing down the regulating valves in the steam supply pipes.

The invention consists in means for preventing overheating in steam superheaters 50 comprising a superheater safety valve with means for varying the blow-off pressure of such valve controlled by the temperature in a superheater tube or in the neighbourhood of the superheater tube.

The invention further consists in the improved constructions of superheaters hereininafter described. 55

Referring to the accompanying drawings:

Figure 1 shows a superheater safety valve 60 with means for causing the blow-off pressure to be influenced by the temperature of the steam in the superheater.

Figure 2 shows a modified form in which an increase in the temperature of the steam 65 above a certain degree positively causes the superheater safety valve to lift.

Figure 3 is a vertical section showing a form of the invention in which the blow-off pressure of the safety valve depends upon 70 the temperature of the gases surrounding the superheater.

Figure 4 being a part plan of the same.

Figure 5 is a modification of the form shown in Figure 2. 75

In the form of the invention shown in Figure 1, the safety valve 1 and its gear are mounted on a casting 2. An enlarged superheater tube 3 in series with one of the ordinary coils 4 of the superheater is also rigidly attached to the casting 2. This tube contains a thermostat consisting of a series of concentric tubes 5, 6, which are alternately of steel and of a special alloy which has a high coefficient of expansion with increasing temperature. As these tubes are arranged alternately a considerable cumulative differential expansion is obtained between the outermost of the steel tubes 5 and the central bar 7, and any increase of temperature therefore causes the bar 7 to project further through the casting 2. The collar 8 on the bar 7 is in contact with the bell crank lever 9 which transmits the movement of the bar 7 to the spring cap 10 on the safety valve. The initial compression of the safety valve spring under normal working conditions keeps the bell crank lever 9 and the collar 8 in contact, and any increase in temperature of the steam in the superheater 100 tube 3 causes the safety valve spring cap 10 to lift and so reduces the spring compression and the blow-off pressure of the valve. 95

In order to avoid a large compression of the safety valve spring when the boilers are 105 shut down and allowed to cool a heavy spring 11 with a very small compression and an adjusting hand wheel nut 12 may be pro-

vided on the end of the bar 7. This spring takes up the further movement of the bar after the lever 13 has come into contact with the safety valve cover 14. The hand wheel nut 12 may also be used (whether the spring 11 is fitted or omitted) for adjusting the blow-off pressure in addition to the adjustment obtained by the ordinary nut 15.

It will be noticed that the sleeve 16 through which the end of the nut 15 screws, and which is carried on the end of the lever 13, is free to slide vertically, being constrained only by the lever 13.

In the modified form of the invention shown in Figure 2, the lever 13 operates the safety valve stem 17 itself instead of operating the safety valve spring cap. In this case an increase in temperature in the superheater tube causes the safety valve to be positively lifted.

In the modification shown in Figures 3 and 4, the thermostat 21 is placed in the uptake adjacent to the superheater tubes 22 so that the differential expansion depends upon the temperature of the gases surrounding the superheater. The relay valve 23 is provided with a spring 24 sufficient to keep the valve closed against the steam pressure. A slight expansion of the bar 25 above a predetermined amount will cause the relay valve to lift by the movement of the lever 26, and thereby admits steam by the pipe 27 to the chamber 28 in the safety valve 29. The steam pressure in the chamber 28 acts upon the annular surface 30, thus opposing the safety valve spring 31 and reducing the blow-off pressure of the valve. In this modification the thermostat consists of a flat bar 32 of special alloy riveted at one end to the free end of a double bar 33, 34, which is slidably supported on a bracket 36. The other end of the bar 33 is rigidly attached to the base of the relay valve 23, so that the differential expansion of these bars causes the bar 32 to project further through the uptake the lift the lever 26 and valve 23.

It will be seen that the thermostats may be interchanged, either type being used in any of the examples illustrated. It will also be seen that in either type of thermostat any number of pairs may be utilized to obtain the required amount of movement by differential expansion.

In the modification of the invention shown in Figure 5, the safety valve is provided with two springs 40, 41, which have a double cap connecting piece 42. The lever 13 operates the latter, causing it to be lifted when the influencing temperature increases. Under normal working conditions the adjusting screw 43 is set so as to bring the lever 9 into contact with the end of the bar 7 while the connecting piece 42 is in a free position, the springs 40, 41, being then equally stressed. When the connecting piece

42 is lifted by the lever 13 the spring 40 is further pressed, but the spring 41 has its compression reduced so that the blow-off pressure is correspondingly reduced.

It will be seen that the lever and link transmission gear is not under stress until abnormally high temperatures prevail. The springs 40, 41, need not be of the length shown in the drawing and the spring 40 may conveniently be made much shorter than the spring 41.

Where in the appended claims I refer to the temperature associated with the superheater these terms are used in a generic sense to include means located in the superheater or located in such relation thereto as to be affected by the changes in temperature corresponding substantially to the changes which take place in the superheater.

Having now described our invention, what we claim as new and desire to secure by Letters Patent is:—

1. In combination with a steam superheater for steam boilers, a relief valve controlling the exit of steam from the superheater and operating means for said valve, including a thermostat associated with said superheater and having control of said valve to cause it to blow off steam proportionally to the rise in temperature of said superheater consequent upon the demand for steam being reduced or ceasing.

2. In combination with a steam superheater for steam boilers, a relief valve controlling the exit of steam from the superheater, a thermostat associated with said superheater, and means for controlling said valve from said thermostat, whereby the valve will blow off when the temperature rises within the superheater, consequent upon the demand for steam being reduced or ceasing.

3. In combination with a steam superheater for steam boilers, a relief valve controlling the exit of steam from the superheater a thermostat associated with the superheater, means for exerting pressure upon said valve against its opening movement and means operated by the thermostat to decrease the pressure of said pressure means upon the valve to permit it to open progressively with increase of temperature in said superheater, substantially as described.

4. In combination with a steam superheater for steam boilers, a relief valve for controlling the exit of steam from the superheater, a thermostat associated with the superheater, pressure means tending to keep said valve closed, a piston on said valve spindle to be acted on by steam in opposition to said pressure means, a relay valve to admit steam to said piston so controlled by said thermostat that increase of temperature in the superheater causes decrease in

blowing-off pressure of said relief valve, substantially as described.

5. In combination with a steam superheater, a blow off valve for the superheater, and thermostatic controlling means associated with the superheater and operating to open said valve when the temperature in the superheater rises to a predetermined

point, consequent upon the demand for steam ceasing or being reduced, substantially as described.

In testimony whereof we have signed our names to this specification.

CHARLES ALGERNON PARSONS.

STANLEY SMITH COOK.
